UNITED STATES PATENT OFFICE

RAYMOND B. SHOEMAKER AND CHARLES L. LAWRENCE, OF NEW YORK, N. Y.

DISHWASHING MACHINE

Application filed August 30, 1927. Serial No. 216,409.

Our invention relates to improvements in apparatus of the character set forth in our application 87,222, filed February 10, 1926, which has now eventuated into Patent 5 1,717,417 dated June 18, 1929. The main object of the invention is to simplify the construction, render it more durable and reliable and to facilitate the construction, adjustment and repair. Another object is to provide 10 means for regulating the water pressure.

Apparatus of this character is particularly intended for installation in apartments and for household use either as new permanent installations or as attachments for old or 15 existing installations.

In its preferred form the apparatus comprises a casing having controllable inlets for hot and cold water and having a single outlet nozzle to which may be attached any form 20 of device for either spraying water and/or soap solution, or for scrubbing as by means of a brush or mop (not shown). The main casing is provided with a flexible bag or reservoir for liquid soap or other chemical 25 which it may be desired to mix with the water or other liquid. For convenience we will hereinafter refer to the liquid as water and to the solution as liquid soap, or soap solution.

The outlet member at the bottom of the 30 casing is also connected with the interior of the soap bag and provided with a valve by which the passage of the soap solution to the outlet may be controlled. The soap bag is spaced apart from the bottom of the casing 35 by a perforated raised platform, and a control or throttle member is provided for regulating the flow of water from the casing and hence regulating the pressure on the reservoir. The soap bag is detachably secured in 40 the casing between the platform at the bottom and the removable cover at the top. A tubular extension from the outlet member provides a convenient means for securing the cover in place.

45 Fig. 1 is a plan view of one form of apparatus embodying our invention.

Fig. 2 is a front view and partial vertical section of the same.

50 Fig. 3 is a transverse sectional view on a vertical plane showing the method of secur-

ing the parts together and controlling the outlet.

Fig. 4 is a horizontal sectional view of the tubular connection to the outlet member on the plane of the line 4—4 of Fig. 3.

55

Fig. 5 is a horizontal sectional view of the outlet member on the plane of the line 5—5 of Fig. 3.

55

Fig. 6 is a detail view of the regulating member.

60

The casing 10 may be of any suitable form and is adapted to be supported in any suitable manner, as for instance, from the faucets 11 and 12 for the hot and cold water.

65

The nozzle or discharge member 13 is preferably secured in a suitable manner within a coupling member 14 in such a manner that the nozzle may be swung from side to side. This coupling collar is preferably screwed on to the lower end of an outlet member 15 which in turn is secured in any suitable manner in the bottom of the casing 10. This outlet member has one or more channels 16 extending vertically through it through which water may pass from the bottom of the casing to the discharge nozzle.

75

The effective size of the passages 16 may be controlled by the rotation of a regulating plate 17 which is mounted on the outlet member 15 within the casing and adapted to be set to provide any desired area of outlet. This plate 17 may be clamped in place by a screw 17a in a slot 17b.

80

A perforated platform 18 is mounted on the outlet member 15 for supporting the lower wall of the soap bag 19 and holding it spaced apart from the bottom of the casing so that water can pass around the sides of the casing to the outlet passages 16. The upper end of the soap bag is preferably provided 85 with a collar 20 adapted to be seated around the mouth of the opening 21 in the top of the casing.

85

The upper end of the outlet member 15 95 preferably has a screw threaded portion 22 which passes through an opening in the bottom of the bag 19. The bag may be reinforced by a washer 19a. The outlet member has a central passage 23 which extends from its upper end to its lower end but is inter-

100

cepted by a passage for the valve 24 which has a transverse passage 25 through which the soap can pass when the passage 25 is in alignment with the passage 23. A small tube 26 is seated in the upper end of the outlet member 15 and provided with openings 27. A tube 28 is screw threaded interiorly at both ends and the lower end is adapted to be screwed on to the tip 22 of the outlet member 15 so as to clamp the bottom of the bag 19 against the platform 18 and hold the bag in place. This tube 28 is provided with openings 29 through which soap solution may pass from the interior of the bag through the openings 27 to the passage 23 in the outlet member.

The cover 30 of the casing rests on the collar 20 of the bag and is clamped in place by a knob 31 which has a threaded stem 32 which screws into the upper end of the tubular extension 28. When it is desired to fill the bag the knob 31 is unscrewed and the cover 30 removed whereupon the bag may be filled by simply pouring the soap solution through the opening in the top. In case the bag is to be removed for repair or replacement the tube 28 is unscrewed using for this purpose the thumb pieces 33, thus releasing the bottom of the bag which may be pulled out from the opening at the top of the casing. When a new bag is to be inserted the hole in its bottom is registered with the inner tube 26 which serves as a guide while the bag is being inserted. The outer tube 28 is then placed over the tube 26 and screwed into place on the upper end 22 of the outlet member 15.

When the apparatus is in use hot or cold water or a tempered warm water may be drawn from the nozzle 13 by proper adjustment of the faucets 11 and 12. When a soapy solution is desired the valve 24 is opened so that the soap solution can pass from the interior of the bag 19 through the openings 29 and 27 and the passages 23 and 25. The pressure of the water, hot or cold as the case may be, against the outside of the bag 19 serves to force the soap solution out at a rate which is substantially proportionate to the pressure. When a soap solution is no longer desired the valve 24 is simply closed so that no more soap is admitted to the nozzle 13.

We claim:

1. In an apparatus of the character described the combination with oppositely directed hot and cold liquid supply pipes, of a mixing chamber into which said supply pipes empty, means for controlling the supply of liquid from each pipe to temper a mixture of liquids from said pipes in said chamber, a material container within said chamber and means for supplying fluid material from said container to the mixture, the quantity of such material supplied varying with the mixture pressure, said chamber and container having a cover in common, and means adjacent said cover by which the container may be freed for removal.

chamber comprising a regulating device for the liquid before it is mixed with the material from said container.

2. A washing machine comprising a casing having a water inlet and an outlet member having a water outlet passage, a collapsible soap reservoir having one wall mounted on said outlet member in said casing said outlet member extending through the wall of said reservoir and communicating with the interior thereof, a valve in said outlet member for controlling the flow of the soap solution to the water outlet passage, a tubular member having a screw threaded engagement with said outlet member for clamping said soap reservoir in place and a cover detachably secured to said tubular member.

3. A washing machine comprising a casing having a water inlet and an outlet member, said outlet member having passages for water and for a soap solution, a valve for controlling the passage of the soap solution, an extension tube from the upper end of said outlet member and an extension clamping tube secured to said outlet member, said casing having an inlet at its upper end, a collapsible soap reservoir held in place in said casing on said extension tube by said clamping tube and having an entrance secured to the edge of the opening in said casing, said tubes formed with passageways communicating from the soap reservoir to the passage in said outlet member to permit soap to pass therethrough and a cover for clamping the entrance end of said soap reservoir.

4. In an apparatus of the character described the combination with hot and cold liquid supply pipes, of a mixing chamber into which said supply pipes empty, means for controlling the supply of liquid from each pipe to temper a mixture of liquids from said pipes in said chamber, a material container within said chamber and means for supplying fluid material from said container to the mixture, the quantity of such material supplied varying with the mixture pressure, said chamber and container having a cover in common, and means adjacent said cover by which the container may be freed for removal.

5. A washing machine comprising a casing having an outlet member with passages for water and soap solution, a valve for controlling the outlet for the soap solution, a throttling plate mounted on the outlet member inside the casing for partially closing the water outlet passage and controlling the exit of water from the casing, a perforated raised platform above said throttling plate and a flexible soap reservoir secured to said outlet member and supported on said platform within said casing a part of said outlet member extending into said reservoir and

the passage for soap solution communicating with the interior thereof.

6. Apparatus of the character described comprising a casing having an opening in the top for the insertion of a bag, an inlet valve for admitting water to said casing, an outlet member having a passage for water and having a neck projecting upwardly with a soap discharge passage, a collapsible bag mounted in the casing on said neck and having an inlet mouth, means for detachably securing the bottom of the bag on the neck of the outlet member comprising a clamping tube, and means for detachably sealing the mouth of the bag in the opening in the casing, and closing the opening and the mouth the interior of said bag communicating with the passage in said outlet member.
- 10 7. Apparatus of the character described comprising a casing having an opening at the top with a detachable cover, hot and cold water inlet pipes connected to the casing, a water outlet member connected to the bottom of the casing, a collapsible bag mounted in the casing and having a mouth at its upper end secured in place by said cover and removable independently of either of said pipe connections, the bottom of said bag being detachably connected to said outlet member, said outlet member having a passage discharging from said bag, and means for detachably securing the bag to the outlet member comprising a clamping tube detachably secured to the outlet member and a guide member secured to the outlet member and extending upward in the clamping tube.
- 15 8. Apparatus of the character described comprising a casing having a valve controlled water inlet and an opening for inserting a bag, an outlet member secured to the bottom of the casing and having a water passage and a soap passage, a collapsible bag substantially filling the inside of the casing and having an inlet mouth and an outlet, means for detachably securing said inlet mouth to the opening in the casing and closing the opening, means for securing the outlet of said bag to the outlet member, said parts being provided with a passage permitting soap to pass through the bag to the outlet member, a valve in the outlet member for controlling the discharge from the bag through the soap passage, the pressure of water in the casing when the inlet valve is open serving to compress the bag and slowly eject its contents when the valve in the soap outlet is also open, and means for varying the effective size of the water outlet to control the back pressure in the casing.
